UNITED STATES PATENT OFFICE.

HENRY ESSEX, OF MEADVILLE, PENNSYLVANIA.

IMPROVEMENT IN PADLOCKS.

Specification forming part of Letters Patent No. 140,617, dated July 8, 1873; application filed May 3, 1873.

To all whom it may concern:

Be it known that I, HENRY ESSEX, of Meadville, in the county of Crawford and State of Pennsylvania, have invented a new and valuable Improvement in Padlocks; and I do hereby declare that the following is a full, clear, and exact description of the construction and operation of the same, reference being had to the annexed drawings making a part of this specification, and to the letters and figures of reference marked thereon.

Figure 1 of the drawings is a representation of my improved padlock with one side removed, to exhibit the interior parts. Fig. 2 is a view of the cover. Fig. 3 is a view of the several bolts used for the purpose of locking a sliding staple.

My invention relates to padlocks; and consists in the novel construction and arrangement of the sections, the sliding bolts and staple having cross-grooves, inclined plane, and check, as hereinafter more fully described. The object of my invention is to furnish a padlock of easy construction, of great strength, of easy management, and still very difficult to pick or to disarrange.

A represents the case of the padlock, and B represents the cover of it. A staple, C, is embedded to half its thickness in the case A of the padlock, and to the remaining half of its thickness in the cover B. The staple C is provided with a number of cross-grooves, c^1 c^2 c^3 , of different widths, the next one to the inner end being the narrowest, and the most distant one the widest. The end of the said staple is tapered on one side, as at c^4 , and has on the opposite side a check or stopping block, D, which slides in a groove, d , in the cover B, and prevents the separation of the staple from the padlock in the act of unlocking. The head of the staple C is bent at e , and thereby forms an eye with the case, when locked. The case A has, beside the recess for the staple, another deeper recess, crossing that of the staple at a right angle, or nearly so. This deep recess contains a number of movable bolts, E E^1 E^2 , with partition-strips g g , to fill up the spaces between the bolts. The bolts E E^1 E^2 are provided with recesses, across which the staple C slides when unlocked. When locked, the said

bolts cross the grooves c^1 c^2 c^3 , either partly or wholly.

To unlock or withdraw the staple C, the bolts are pushed by a key, F, with steps f f^1 f^2 , arranged in such manner that they bring the recesses in said bolts in one line with the recesses of the staple C, forming an uninterrupted passage for the staple. The staple may then be pulled outward until it is checked by the meeting of the block D with the end of the recess d . The bolts E E^1 E^2 , after they are relieved from the staple, resume the old positions with the aid of a spring, G, which bears against the ends of the said bolts, and is jammed with both of its ends into the corners of a segmental depression in the case.

For the purpose of locking the staple C the key F is not wanted, and it is only necessary to push the J-shaped staple back into the case. The point of the staple enters thereby the recesses of the bolts E E^1 E^2 ; the inclination c^4 pushes them in the right position, so the main part of the staple may enter them. As the narrowest slot c^3 passes the wide bolt E first, and the middle-sized bolt afterward, there is no danger of the bolt E entering the slots c^3 or c^2 , and locking the staple C prematurely and imperfectly. The same is the case with the middle-sized bolt E^1 ; and the staple can only be locked when the slots c^1 c^2 c^3 arrive at their corresponding bolts—that is, when the staple C is pushed down to its full allowance.

What I claim as new, and desire to secure by Letters Patent, is—

1. The combination of the sections A and B, the sliding staple C with inclined plane c^4 , check D, recess d , bolts E E^1 E^2 , removable partition-plates g , and spring G, substantially as specified.

2. The construction and arrangement of the grooves c^1 c^2 c^3 , and sliding bolts E E^1 E^2 , and the inclined plane c^4 on the sliding staple C, substantially as specified.

In testimony that I claim the above I have hereunto subscribed my name in the presence of two witnesses.

HENRY ESSEX.
